UNITED STATES PATENT OFFICE

EDWARD S. SAVAGE AND CHARLES F. FRIEDRICH, OF ROCHESTER, NEW YORK

DESIGN FOR A FIGURE TOY

Application filed August 6, 1932. Serial No. 44,538. Term of patent 7 years.

To all whom it may concern:

Be it known that we, EDWARD S. SAVAGE and CHARLES F. FRIEDRICH, citizens of the United States, residing at Rochester, in the county of Monroe and State of New York, respectively, have invented a new, original, and ornamental Design for a Figure Toy, of which the following is a specification, reference being had to the accompanying drawing, forming part thereof.

The drawing illustrates a perspective view of the design, the shaded lines indicating different colors, and the ornamentation on the opposite side of the design being the same as that on the side shown.

We claim:

The ornamental design for a figure toy as shown and described.

EDWARD S. SAVAGE.
CHAS. F. FRIEDRICH.
